UNITED STATES PATENT OFFICE.

WILLIAM H. HART, JR., OF PHILADELPHIA, PENNSYLVANIA.

TOY MONEY-BOX OR SAVINGS-BANK.

1,179,720.

Specification of Letters Patent. Patented Apr. 18, 1916.

Application filed October 20, 1915. Serial No. 56,852.

To all whom it may concern:

Be it known that I, WILLIAM H. HART, Jr., a citizen of the United States, residing in the city and county of Philadelphia, State of Pennsylvania, have invented a new and useful Toy Money-Box or Savings-Bank, of which the following is a specification.

My invention consists of a toy money box or saving bank of paper or other material having its sides and bottom formed each of double walls, the sides having inlets leading to the spaces between their double walls, and the bottom having members adapted to be tucked or fitted one into the other and secured, thus closing said bottom, thus preventing the escape or abstraction of the money or coin through the bottom and sides, said sides and bottom being adapted to be folded in flat condition, all as will be hereinafter more fully described.

The invention is satisfactorily illustrated in the accompanying drawing, but the important instrumentalities thereof may be varied, as long as they are included in the scope of what is claimed.

Figure 1 represents a perspective view of a toy money box or saving bank embodying my invention. Fig. 2 represents a section thereof on the line $x-x$ Fig. 1. Fig. 3 represents an end elevation of the box in folded or knocked down condition. Fig. 4 represents a plan view of what may be termed the blank from which my box or bank is formed primarily. Fig. 5 represents a plan view of said blank in the next step of transformation into the box or bank. Fig. 6 represents a section of a portion of the bottom member of the box in separated condition. Fig. 7 represents a vertical section of the box or blank in a slightly modified form.

Similar numerals of reference indicate corresponding parts in the figures.

Referring to the drawings 1 designates the toy money box or bank sometimes denominated as a mite box constructed in accordance with my invention, the same being of pyramidal form and having double side walls 2, access between which is had through the openings or inlets 3 in the outer walls thereof, the box or bank having a bottom 4 which is composed of opposite flat tubular members 5 and 6 which are adapted to be tucked into each other telescopically, thus closing said bottom, whereby the money or coin cannot drop out, escape through, or be

abstracted at said bottom. In the underside of the bottom 4 is a crease line 7 by which said bottom may be folded upwardly between the side walls 2 of the box, and at the top of the box is the crease line 8 which forms a hinge for said side walls 2 at said top, permitting said walls to be folded toward each other with the folded bottom 4 between the same, whereby the box is flat or in knocked down condition, as shown in Fig. 3. To the inner faces of the outer walls 2 of the box is secured the piece 9 of comparatively stiff paper or card board, forming reinforces for said walls. The center of said piece 9 has on it the crease 10 in harmony with the crease line or hinge 8, at the top of the box, so as to fold with said box, said center having also in it, the opening 11 which is in communication with the inlets 3 so that said reinforced piece 9 presents no obstruction to the entrance of the money or coin through the inlets 3 into the box.

In carrying out my invention, I take a piece of paper 12 or other suitable material of quadrilateral form which comprises a blank from which the box or bank is formed. Said piece is creased in longitudinal direction by the lines 13, and in transverse direction by the lines 14 and 15, and the central line 8, said lines 8, 15 and 14 crossing the lines 13, said line 8 forming the crease line or hinge at the top of the box when made up. When the box is made up, the crease lines 15 forms the folding crease 90 line 7 in the bottom of the box. See Figs. 1 and 3.

In setting up the box, the sides of the paper or material are folded inwardly on the crease lines 13 one overlapping the other and being gummed together, thus forming the inner members of the side walls 2, and a flat tubular shape as in Fig. 5, where a portion of one of said members is broken away to show some of the gum or adhesive material which is employed to unite the contiguous members at the overlap said members thus being closed preventing subsequently the money or coin from escaping through or being abstracted at the sides of said members. The ends of the paper are now folded inwardly on the inner members of the side walls 2, thus producing the tubular members 5 and 6 of the bottom 4. Then the side walls are folded partially toward each other on the top line 8, and the members 5 and 6 are tucked one into the other,

or telescopically so, producing the closed bottom 4, and completing the box in condition for use as in Fig. 1 the box being hollow from end to end within the inner members of the side walls 2 and those of the bottom 4.

If desired, the members 5 and 6 may be gummed or pasted together, to prevent disconnection of the same, but for ordinary purposes the friction of said members 5 and 6 will be sufficient to hold them in closed condition.

As stated before, the walls 2 and bottom 4 as composed of the members 5 and 6 may be folded upwardly on the existing crease line 7 of said bottom, and the side walls 2 brought together with said bottom between them, producing the flat or knocked down condition of the box, as shown in Fig. 3.

In Fig. 7 I show another embodiment of my invention where one of the tubular members 5 or 6 of the bottom is formed with a tongue 16 which is adapted to be tucked into the lower ends of the adjacent side walls 2, so that said tubular member remains as the bottom of the box and is adapted to be folded up on the crease line 7, as in the previous construction.

The crease lines 14 at the lower ends of the side walls 2 and sides of the bottom 4, form folds of the material of the box, at what may be called the lower corners of the box, preventing the entrance of the money or coin from said walls into said bottom.

Having thus described my invention what I claim as new and desire to secure by Letters Patent, is:—

1. A toy money box of the order stated formed of double side walls, and a bottom

continuous inwardly of said side walls, said bottom being formed of tubular members adapted to be fitted telescopically to each other, an exterior member of said side wall having therein an inlet leading into the space between said exterior and the inner members of said side walls.

2. A toy money box of the order stated formed of double side walls, and a bottom continuous inwardly of said side walls, said bottom being formed of tubular members adapted to be fitted telescopically to each other, an exterior member of said side wall having therein an inlet leading into the space between said exterior and the inner members of said side walls, and a reinforcing member on an inner face of said side walls, foldable and unfoldable with said walls and adapted to uncover the inlet of the box.

3. A toy money box of the order stated formed of a blank having inlet openings therein and longitudinally extending crease lines in the side portions of said blank, transverse extending crease lines in the end portions of the blank crossing the first named lines, producing members for constructing a box of pyramidal form as follows:—double side walls, the space between which comprises the place of deposit of money or coin accessible through said inlet openings, and a bottom of flat tubular members adapted to be fitted telescopically to each other, said bottom being continued inwardly from said side walls.

WILLIAM H. HART, JR.
